UNITED STATES PATENT OFFICE.

ALEXANDER S. LEVY, OF PHILADELPHIA, PENNSYLVANIA.

DESIGN FOR A BEEHIVE-BUTTON.

47,466.

Specification for Design.

Patented June 15, 1915.

Application filed January 2, 1915. Serial No. 311. Term of patent 3½ years.

To all whom it may concern:

Be it known that I, ALEXANDER S. LEVY, a citizen of the United States, residing at 3654 North Twenty-first street, in the county of Philadelphia and State of Pennsylvania, have invented a new, original, and ornamental Design for Beehive-Buttons, of which the following is a specification, reference being had to the accompanying drawing, forming part thereof.

The title of the design is "Bee-hive button."

The figure is a plan view of a "bee-hive button," showing my new design.

I claim:

The ornamental design for a "bee-hive button," as shown.

ALEXANDER S. LEVY.

Witnesses:

MARY AMBROSE,
MARTIN H. KELLER.
